UNITED STATES PATENT OFFICE.

CHARLES KINGSLEY BROWN, OF PENTICTON, BRITISH COLUMBIA, CANADA.

INCANDESCENT LAMP.

Application filed November 21, 1921. Serial No. 516,848.

To all whom it may concern:

Be it known that I, CHARLES KINGSLEY BROWN, a subject of the King of Great Britain, and a resident of Penticton, Province of British Columbia, in the Dominion of Canada, have invented certain new and useful Improvements in Incandescent Lamps, of which the following is a specification.

10 This invention relates to improvements in incandescent lamps.

The primary object of the invention is to provide an electric lamp of the above character which may be used a relatively 15 long period without renewing the filaments therein.

It is also an object of the invention that the electric lamp be adapted to operate at a comparatively good efficiency.

20 It is also within the objects of the invention that the manufacturing cost of the light be comparatively small.

Other objects will hereinafter appear in the detailed description to follow.

25 In carrying out the invention it is contemplated to provide an electric lamp of the incandescent type with a plurality of filaments which may be separately and individually energized from the same source of supply. In the use of such a light one filament may be used until burnt out and then another used etc., until all the filaments have 30 become useless and in this way increasing the life of a lamp in direct proportion to 35 the number of filaments employed.

The invention is illustrated by way of example in the accompanying drawings, in which:—

Figure 1 is a perspective view of an incandescent lamp with which the present invention is incorporated,

Figure 2 is a vertical sectional view of the same,

Figure 3 is a top plan view of the same.

40 Referring to the drawings more particularly, 10 indicates a lamp bulb which in this instance is of a large type, 11 the screw plug or base of the lamp and 12 the usual cement for securing the base to the bulb 45 and sealing the same.

In the present case the bulb is formed with the usual filament supporting and sealing tube 13, and through which there is 50 extended the wire 14, said wire having its upper end electrically connected to the base or screw plug 12 as at 15, and having con-

nected at its lower end the one end of a plurality of filament wires 16. The other end of each filament wire is secured to a wire 17 and each of the wires 17 are extended upwardly through the sealing tube 13 and cement 12 and connected to the lower end of a vertical tubular sleeve or socket 18 embedded in the cement 12. In the present instance the filament wires 16 are three 55 in number and likewise the sockets 18 are three in number, as shown in Figure 1.

Centrally of the screw plug 11 at the upper end thereof there is embedded in the cement 12 an additional tubular sleeve or 70 socket 19 which has fitted therein a pin 20, said pin being reduced at its upper end as at 21 and having riveted thereto the switch blade generally indicated by the reference numeral 22. The switch blade 22 consists 75 in a resilient metal ribbon which is doubled upon itself, and the free ends riveted to the pin 20, as shown, and the two plies of ribbon bent as at 23 to form the downwardly extending portion 24, the plies forming the 80 same being spaced from each other and adapted to frictionally fit within either of the tubular sections 18. Also it may be pointed out that by riveting the switch blade 22 to the pin 21 a head is formed upon the 85 upper end of the pin 20 as at 25 which is adapted to serve as the contact point or one electrode of the incandescent lamp, the other electrode being the screw plug 11.

In the use of the present incandescent 90 lamp, the switch 22 is positioned for connecting one of the tubular sockets 18 with the central socket 19 or pin 20, and thus connecting the wire 17 associated with the tubular socket 18 with one electrode of the 95 lamp. Now as the screw plug 11 is inserted in the socket connected to a suitable source of electric current supply the path of the current would be through the wire 17 with which the switch member 24 is connected and then through the associated filament wire 16 and from thence through the common wire 14 to the screw plug. This filament could be used until the same is burnt out and then the switch 22 would be 100 transferred or moved so that the same would establish a connection with another of the filaments 16, the circuit in each instant returning through the common wire 14. As is obvious by this arrangement the life of the lamp may be greatly prolonged and at 105 the same time in no way lowering the effi-

ciency of the same. The manner in which the switch 22 can be made to connect with the different wires 17 is thought to be clearly obvious and no detailed description thereof need here be made. It may be mentioned however that the switch 22 will in no way interfere with the positioning of the plug 11 in the standard form of socket.

I claim:

10. 1. In a multiple filament incandescent lamp, a plurality of filaments, one end of each of said filaments being connected to the shell contact of the lamp, the base of said lamp having a central contact in its free end and a plurality of sockets corresponding in number to the filaments arranged about said central socket, the last named sockets having conducting walls and each of said last named sockets being electrically connected to the other end of one of said filaments, and means removably positioned in the central socket and in one of the other sockets serving as a central contact for said lamp and also serving to electrically connect the walls 25 of one of said sockets surrounding the central socket with said central contact.

2. In a multiple filament incandescent lamp, a base, a sleeve carried by the base providing a central socket, a plurality of other sleeves arranged circumferentially thereof also providing sockets, and a member which is held in place in the sockets when the lamp is screwed into a receptacle, said member including a pin which is fitted in the central socket, and an arm carried by 35 the pin fitted into any one of the other sockets.

3. A multiple incandescent lamp having a base, a sleeve carried centrally of the base, a plurality of circumferentially disposed 40 non-circular sockets, and a substantially U-shaped member constituting a connector being held in position when the lamp is screwed into a receptacle and being provided with a head to make contact with a terminal 45 of the receptacle, said member consisting of a pin slidable and revoluble in said central socket, and an L-shaped arm carried by the pin formed of a member doubled upon itself to provide a looped end for frictionally en- 50 gaging the walls of any of the other sockets.

CHARLES KINGSLEY BROWN.
